UNITED STATES PATENT OFFICE.

ALFRED W. RAM, OF WASHINGTON, DISTRICT OF COLUMBIA, ASSIGNOR TO WILLIAM H. FINCKEL, JR., TRUSTEE, OF WASHINGTON, DISTRICT OF COLUMBIA.

TRAFFIC SIGNAL.

Application filed June 29, 1921. Serial No. 481,314.

To all whom it may concern:

Be it known that I, ALFRED W. RAM, a citizen of the United States, residing at Washington, in the District of Columbia, have invented a certain new and useful Improvement in Traffic Signals, of which the following is a full, clear, and exact description.

The object of this invention is to provide a signaling device adapted primarily for regulating vehicular traffic on city streets, but adaptable also to the regulation of the traffic of road vehicles at the intersection of roadways with railways; and the invention contemplates such a device as will allow a certain predetermined number of vehicles to pass in one direction before any vehicles are allowed to pass in an intersecting direction, but capable of passing single vehicles alternately in both such directions when no more than one such vehicle approaches from either direction at a time.

To this end, the invention consists in a traffic signal adapted to be located at the intersection of lines of vehicular traffic, such signal being operatively connected with devices located in the line of vehicular traffic and adapted to be actuated by vehicles, whereby when a vehicle approaches said intersection and actuates one of said devices, said signal will be operated to present to the driver of such vehicle a signal that he may proceed, presenting at the same time to the drivers of vehicles approaching from a direction intersecting that travelled by said first-mentioned vehicle, a signal to stop; and the invention consists further in means whereby the signal and devices may be so modified as to adapt the invention to use in connection with roadways intersecting railways, all as I will proceed now to explain and finally claim.

In the accompanying drawings illustrating the invention, in the several figures of which like parts are similarly designated, Figure 1 shows in perspective the general arrangement of the signal and devices of my invention at a street crossing. Fig. 2 is a sectional elevation showing one of the devices actuated by a vehicle for operating the signal. Fig. 3 is a view showing a portion of the mechanism shown in Fig. 2 so modified as to adapt the device for use in connection with railways. Fig. 4 is a sec-

tional elevation showing on a larger scale the mechanism operated by the device shown in Fig. 2. Fig. 5 is a sectional elevation showing the mechanism for accomplishing the readjustment of the mechanism shown in Fig. 4 after the passage of a vehicle. Fig. 6 is a sectional elevation showing the signal proper and its connected operating devices. Fig. 7 is a section taken on the line 7—7 of Fig. 6. Fig. 8 is a view similar to Fig. 7 but showing an arrangement of the parts suitable when the invention is used in connection with railways. Fig. 9 is a wiring diagram illustrating the electrical connections of the various mechanisms when the device is designed for use at the intersection of roadways. Fig. 10 is a wiring diagram showing the electrical connections of the device when adapted for use in connection with railways. Fig. 11 shows a modified form of the device actuated by vehicles.

Referring more particularly to the drawings, it will be seen that I provide a signal member indicated generally by the numeral 1 comprising a base member 2, adapted to be suitably secured to the roadway as by a plate 3 cooperating with a flange 4 upon a casing 5 embedded in the roadway. The base 2 is provided with a bearing member 6 through which passes a revoluble standard 7 carrying at its upper end a suitable sign 8 which may be illuminated, if desired, having four arms bearing the legends or signals "Go" and "Stop," as is customary with ordinary traffic signals. As the means of illuminating the sign forms no part of this invention, it will suffice to say that the arms may be of box-like construction as shown, and provided with transparent or other plates 9 bearing the above-mentioned signals, those bearing the signal "Go" being preferably colored green with white lettering and those bearing the signal "Stop" being colored red with white lettering, as is the common practice, and each arm having within it electric or other illuminating means.

Within the casing 5 is mounted a pair of solenoids or like electromagnets 10 and 11, provided with a slidable core 12 connected by means of a lever 13 and pin 14 with the standard 7, this core 12 being adapted to be held fixedly so that the signal will remain in either "Go" or "Stop" position.

against extraneous influences, such as wind or meddling, by means of a detent 15 co-operating with a recess or notch 16 in the core, this detent being connected with or 5 forming a part of the core of a solenoid 17 electrically connected with both of the solenoids 10 and 11 by a part winding from each so as to operate to withdraw the detent 15 from the recess 16 upon the energizing 10 of either solenoid 10 or 11. The detent is held normally in engagement with the notch by means of a spring 18. Movement of the standard from "Go" to "Stop" 15 position and vice versa is limited by a pin 19 cooperating with a slot 20 in the bearing member 6.

Located in the roadway, at such a distance from the street intersection as would allow a vehicle travelling at an ordinary 20 rate of speed to stop before reaching such intersection, is a device comprising a pair of plates 21 and 22 (see Fig. 2), the plate adapted to be first contacted with by the 25 wheels of an approaching vehicle having a blunt edge 23 for a purpose hereinafter appearing, and both of the plates being hingedly connected to a rod 24 mounted in a well 25 and having its lower end pivotally connected as at 26 with a plunger 27 working 30 in a socket 28 and pressed normally upwardly by a spring 29 of such tension as to be depressed only by vehicles as heavy or heavier than a motorcycle. This rod 24 is provided with a lug 30 adapted to normally 35 rest upon a projection 31 formed upon the side of the casing of the well 25 so that the rod may be moved downwardly only by a vehicle so approaching as to first contact with the plate 21 and by engagement of the 40 wheels of said vehicle with the blunt edge 23 of said plate push it forward so as to release the lug 30 from the projection 31. Immediately upon the passage of the vehicle 45 entirely over the plates 21 and 22, the spring 29 will return the rod 24 to its upper position and the lug 30 will be forced to engage the projection 31 by means of a pivoted link 32 connected with the rod and with the side 50 of the casing tending to force the rod toward said projection as it is raised by the spring 29. By this arrangement, it will be seen that any vehicle approaching the device so 55 as to strike the plate 22 first, will not operate the rod 24 because it will be held in a raised position by means of the lug and projection.

Mounted adjacent the well 25 is a casing 33 containing mechanism for establishing an electric circuit through the solenoids of the signal, this mechanism including a shaft 34 60 mounted in bearings in the casing and extending through one side thereof and having mounted upon this extension a ratchet wheel 35 bearing a plurality, in this case eight, pins 36, with which cooperates a pusher 37 65 provided with a tooth 38. The ratchet

wheel has a number of teeth 39 equal in number to the number of pins 36 and these teeth are engaged successively by a pawl 40. By means of this mechanism it will be seen that as the vehicle passes over the plates 21 70 and 22 in proper operating direction, the rod 24 will be depressed and moved forward twice, once as the front wheels pass over, and once as the rear wheels pass over, and at each movement of this rod, the pusher 37 75 will rotate the ratchet wheel 35 through a distance equal to the space of one tooth and impart a similar movement to the shaft 34.

Within the casing 33 and mounted upon the shaft 34 is a cam 41 having only one 80 high surface 42 adapted to successively engage a plurality of push rods 43 slidably mounted in guides 44 and having notches 45 cooperating with spring pressed pins 46 whereby the rods are held in either depressed or raised position. Each push rod 43 carries a pair of spring contacts 47 co-operating with stationary contacts 48 carried by insulating blocks 49 mounted upon the casing, these stationary contacts being 90 electrically connected with one of the solenoids 10 or 11 as the case may be, as will be later described. Carried by the guides 44 is a pair of electro-magnets 50 so arranged that when energized they will attract keepers 51 mounted on the push rods 43 to return 95 said push rods to retracted or depressed position and open the circuit through the solenoid.

By this arrangement, it will be seen that 100 when a vehicle operates this mechanism, the cam will be turned to the position shown in Fig. 4, when the front wheels of the vehicle depress the rod 24, thus establishing a circuit through the solenoid of the signal, and when the rear wheels of the vehicle depress the rod 24, the cam will be turned out of engagement with the push rod and to a position intermediate the push rod just operated and that next in order, the push rod just 110 operated being held in raised position to maintain the electrical circuit through the solenoid of the signal by means of its notches 45 cooperating with the pins 46.

At a position in the street closely adjacent 115 the intersection is a second device similar in every respect to that shown in Fig. 2, but instead of being connected for operating the mechanism shown in Fig. 4, is arranged to operate the mechanism shown in Fig. 5, 120 which comprises a casing 52 provided with a shaft 53, similar to the shaft 34, and extending through one side of the casing and carrying a ratchet wheel similar to the ratchet wheel 35. Within the casing 52 and upon the shaft 53 is mounted a cam 54 having one high point 55 adapted to cooperate in order with a plurality of contact makers 56, comprising pivoted arms bearing contacts 57 adapted to make contact with terminals 125 130

58 to which are connected wires leading to the electromagnets 50. These arms are normally held depressed by springs 59 which force them against stops 60.

- 5 By the use of this device, it will be seen that when the vehicle has passed over the plates 21 and 22, which operate the mechanism in the casing 33 and has raised the push rods 43 to establish a circuit through 10 the solenoid of the signal, and has then travelled through the intervening space of the roadway between that device and the similar device operating the mechanism in the casing 52, last described, and has operated this mechanism, the front wheels of 15 the vehicle will have turned the cam 54 to the position shown in Fig. 5, and will have established an electrical circuit through the electromagnets 50 and retracted the push 20 rod 43 to its depressed position by attracting the keeper 51, thus breaking the circuit through the solenoid of the signal. The rear wheels will then turn the cam 54 so as to permit disengagement of the contacts 57 25 from the terminals 58 and thereby break the circuit through the electromagnets 50.

When in the apparatus as illustrated, four vehicles pass over the device controlling the mechanism contained in the casing 52, the 30 rear wheels of the last vehicle of the four to pass over the device will move the high point 55 of the cam 54 into position to operate and pass by the circuit breaker 61, which, as will be later described, controls the 35 whole circuit for the solenoid of the signal on that particular portion of the roadway, thereby making it impossible, until another vehicle has passed over the device controlling the mechanism in casing 33, for the signal to be moved to the "Go" position for 40 that portion of the roadway, and giving vehicles approaching in the intersecting direction right of way.

Referring now to the wiring diagram shown in Fig. 9, the operation of the electrical devices of the invention is substantially as follows:—The diagram illustrates a signal and the controlling devices therefor for one angle only of a pair of intersecting streets, the other angle thereof comprising merely a duplication of the devices shown with the exception of the signal proper and its solenoids. Assuming that a vehicle approaches the intersection from the direction indicated by the arrow A, Fig. 1, the front wheels of this vehicle will depress the plates and operate the device in the casing 33, which we will call the circuit establishing mechanism, to energize the solenoid 62 50 through the contacts 47 and 48, wires 63, 64, circuit breaker 61 and wire 65, at the same time energizing solenoid 17 to actuate the 55 detent 16, to release and move the signal so that the word "Go" thereof will be presented to the driver of the vehicle. How-

ever, should another vehicle have entered the street indicated by the arrow B, the solenoid 66 will have been energized in the same manner through the wires 67, 68 and 69, and as the pull of each solenoid upon 70 its core is the same, the solenoid 66 having been first energized and having the greater portion of the core within it and subject to its influence, will maintain the signal in such position that it will show the signal 75 "Stop" to the vehicle entering at A and "Go" to the vehicle entering at B.

Assuming now that no vehicles are approaching in the direction of the arrow B and that the vehicle approaching in the direction of the arrow A has turned the signal so that it reads "Go" for vehicles approaching in that direction, and that three other vehicles are following it in that direction, these three vehicles will successively 80 operate the push rods 43 so that all of them are in contact making position. Then, as these four vehicles pass over the devices controlling the mechanism mounted in the casing 52, which we will call the circuit interrupting mechanism, they will successively 85 energize all of the pairs of electromagnets 50 and return all of the push rods to depressed position, thereby breaking the circuit, the rear wheels of the fourth vehicle 90 causing the cam 54 to operate the circuit breaker 61 as above described, thereby breaking the entire circuit for the solenoid 62 momentarily and allowing vehicles a chance to pass in the direction of arrow B. 95 It will thus be seen that after four vehicles have passed in one direction, other vehicles coming in that direction will have the signal "Stop" confronting them if vehicles approaching in the direction of the arrow B have operated the solenoid 66, for the reason that immediately the solenoid 62 is de-energized by the breaking of its circuit through 100 circuit breaker 61, the solenoid 66, which has been energized, will draw the core into it 105 and thereby rotate the signal.

Obviously, therefore, the traffic signal, in the case shown, will operate automatically to allow one or more vehicles up to four to pass in one direction before vehicles are allowed to pass in the other direction, or vehicles may pass alternately in each direction, so long as there is no vehicle waiting in the space between the circuit establishing and circuit interrupting mechanisms of the 115 street of the intersecting direction.

In adapting the invention for use with roadways intersecting railways, it is desirable to have the signal set normally at "Stop" for vehicles approaching on the 120 roadway and this necessitates some minor changes in the apparatus.

One of such changes is that shown in Fig. 8 in which a spring 70 is used for normally holding the signal in "Stop" position or for 125

immediately returning it to "Stop" position after it has been turned to "Go" position by a vehicle in the roadway.

- A further change in the mechanism is that 5 inasmuch as there is no need for allowing a number of vehicles to pass over the railroad tracks at a time, the railroad trains having the right of way at all times, only one circuit establishing contact and only one circuit 10 interrupting contact for the one circuit establishing contact is necessary. Therefore, instead of having the ratchet wheel 35 for the circuit establishing mechanism, I need have only a lever 71 which will oscillate 15 in unison with the oscillation of the rod 24 through a link 72 to move the high point 42 of the cam 41 into and out of engagement with the push rod 43. A similar connection of lever and link with the cam 54 of the circuit 20 interrupting mechanism will be substituted for the ratchet wheel of that mechanism.

In the diagram, (Fig. 10) 73 indicates the rails of the railway, 74 the solenoids of the 25 road signals energized by the trains, 75 the solenoids energized by vehicles on the roadway, 76 the circuit establishing mechanism, 77 the circuit interrupting mechanism, and C and D block signals.

30 As above stated, the road signals are normally set to present the signal "Stop" to drivers of vehicles on the roadway, so that when a train enters the portion of the rails 73 controlling the solenoids 74 these solenoids will be energized and the signals will therefore remain in the "Stop" position and cannot be changed by vehicles approaching on the roadway because of this previous energizing of the solenoids 74 whose action 35 is augmented by springs 70 and cannot be overcome by energizing solenoids 75. However, if there is no train travelling in either direction on that portion of the railway controlling solenoids 74, a vehicle approaching 40 on the roadway will operate the solenoid-controlling mechanism to energize the solenoids 75 and will overcome the springs 70 and shift the signals to "Go." Of course, the section of the rails 73 controlling the 45 solenoids 74 will be of such extent in both directions from the roadway as to make passage of road vehicles over the tracks safe should a train enter the section as a vehicle is crossing the tracks.

50 The two signals are connected in parallel so that both will operate simultaneously.

If desired, my signals may be so connected electrically as to operate with the block signals of the railroad, such block signals 55 being arranged to some extent to accommodate the arrangement of my signals. In the arrangement shown in the diagram, a block signal C will be located adjacent the point at which my signal is electrically connected with the rails 73 first contacted by a

train, and a block signal D arranged at the point where the train ceases to affect my signal. Therefore block signals C will be set and unset simultaneously with my signal, and block signals D will be set when the train ceases to affect my signal and will be unset when the train leaves the block. By this arrangement the same source of electricity used for operating the block signals may be used for operating my signals 75 if desired.

While the invention is shown and described in what I now consider to be its preferred form, it is conceivable that various changes may be found advisable in later 80 developments. For example, the plates 21 and 22 instead of reaching entirely across the roadway, as shown, may extend only part way across from the right-hand side, especially those actuating the circuit interrupting mechanism, and in such an installation it will not be essential that the device be provided with means for preventing its actuation by vehicles travelling in the direction opposite to the direction of those by 90 which it is intended to be actuated. To meet this condition, I have devised the mechanism shown in Fig. 11, which comprises a rod 78 to which the plates 21 and 22 are connected, the plate 21 like 22 having 95 a beveled ground contacting edge instead of the blunt edge 23. This rod 78 is mounted to slide vertically in a casing 79, provided at its lower end with a chamber 80 in which is mounted a spring 81 bearing against 100 a seat 82 on the end of rod 78 and adapted to hold the rod normally in full upwardly projected position as determined by the stop 83. Pivotedly connected to the rod 78 is a hook member 84 which extends through an opening in the casing 79 and is so arranged with relation to the ratchet wheel 85 of the circuit establishing or circuit interrupting mechanism as to successively engage pins 86 105 thereon. This hook member 84 is held normally in engagement with the pins 86 by a spring 87. The pawl 88 prevents backward rotation of the mechanism. The distance between the pins on the ratchet and the full downward movement of the rod 78 is so proportioned that each downward movement of the rod will, through the hook member 84, advance the ratchet wheel through an arc of forty-five degrees, as is the case in the embodiment of the device previously described.

110 What I claim is:—

1. In a traffic signal, the combination with intersecting traffic lanes, of signal means for controlling traffic across the intersection, and vehicle actuated means for controlling 115 said signal means, whereby not more than a predetermined number of vehicles may pass in one direction before the signal means is actuated to signal approach of vehicles in an intersecting direction.

2. In a traffic signal, the combination with intersecting traffic lanes, of signal means for controlling traffic across the intersection, and means arranged in the traffic lanes and responsive to the movement of vehicles for controlling said signal means, whereby not more than a predetermined number of vehicles may pass in one direction before the signal means is actuated to signal approach of vehicles in an intersecting direction.
3. In a traffic signal, signal means located adjacent to the intersection of lines of traffic, vehicle actuated means for imparting movement to said signal means to signal approach of traffic in one direction and to permit passage of a predetermined number of vehicles in that direction, and including means for rendering said first mentioned means momentarily incapable of actuating said signal means after passage of said predetermined number of vehicles and thereby permitting actuation of the signal means to signal approach of vehicles in an intersecting direction.
4. In a traffic signal, signal means located adjacent to the intersection of lines of traffic, means associated with said signal means for imparting movement thereto, means for energizing said movement-imparting means, means for interrupting the influence of said energizing means, vehicle actuated means operatively connected with said energizing means, and vehicle actuated means operatively connected with said interrupting means, the two said vehicle actuated means being spaced apart a distance sufficient to accommodate a predetermined number of vehicles, and connections between the energizing means and the interrupting means whereby said signal means having been moved by the actuation by a vehicle of said energizing means is incapable of returning to its initial position until the actuation of the interrupting means by all vehicles contained in the space between the two vehicle actuated means.
5. In a traffic signal, the combination with intersecting traffic lanes, of signal means for controlling traffic across the intersection including an electrically controlled operating mechanism, and means including vehicle actuated switch mechanism for energizing and deenergizing said operating mechanism, whereby not more than a predetermined number of vehicles may pass in one direction before the signal means is actuated to signal approach of vehicles in an intersecting direction.
6. In a traffic signal, the combination with intersecting traffic lanes, of signal means for controlling traffic across the intersection including an electrically controlled operating mechanism, and means including vehicle actuated switch mechanism for energizing said operating mechanism and vehicle actuated switch mechanism for deenergizing said operating mechanism, whereby not more than a predetermined number of vehicles may pass in one direction before the signal means is actuated to signal approach of vehicles in an intersecting direction.
7. In a traffic signal, the combination with intersecting traffic lanes, of signal means for controlling traffic across the intersection including an electrically controlled operating mechanism, switch mechanism for energizing said operating mechanism, switch mechanism for deenergizing said operating mechanism, and means including vehicle actuated devices for actuating said switch mechanisms, whereby not more than a predetermined number of vehicles may pass in one direction before the signal means is actuated to signal approach of vehicles in an intersecting direction.
8. In a traffic signal, the combination with intersecting traffic lanes, of signal means for controlling traffic across the intersection including electrically actuated operating mechanism, a source of electrical energy, connections between said source and said operating mechanism, and vehicle actuated switch mechanism for energizing and deenergizing said operating mechanism interposed in the connections between said operating means and the source of electrical energy, whereby not more than a predetermined number of vehicles may pass in one direction before the signal means is actuated to signal approach of vehicles in an intersecting direction.
9. In a traffic signal, the combination with intersecting traffic lanes, of signal means for controlling traffic across the intersection including electrically controlled operating means, means including vehicle actuated circuit establishing means and vehicle actuated circuit interrupting means for controlling said operating means whereby not more than a predetermined number of vehicles may pass in one direction before the signal means is actuated to signal approach of vehicles in an intersecting direction, said circuit establishing and circuit interrupting means including switch members equal in number to the predetermined number of vehicles.
10. In a traffic signal, the combination with intersecting traffic lanes, of signal means for controlling traffic across the intersection including electrically controlled operating means, means including vehicle actuated circuit establishing means and vehicle actuated circuit interrupting means for controlling said operating means whereby not more than a predetermined number of vehicles may pass in one direction before the signal means is actuated to signal approach of vehicles in an intersecting direction, said circuit establishing and circuit interrupting means including switch members equal in number to the predetermined number of vehicles.

number to the predetermined number of vehicles, and said circuit interrupting means including a circuit breaker for rendering temporarily inoperative all of the switches 5 of said circuit establishing means.

11. In a traffic signal, the combination with intersecting traffic lanes, of signal means for controlling traffic across the intersection, means responsive to electrical energy 10 for imparting signalling motion to the signalling means, means for actuating said motion-imparting means including a plurality of circuit establishing mechanisms, one of which is located in each traffic lane and arranged 15 for actuation by vehicles to establish a circuit through said motion imparting means, and a plurality of similarly located circuit interrupting mechanisms arranged for similar operation subsequently to the operation of 20 the circuit establishing mechanisms to interrupt the circuit through the motion imparting means, whereby not more than a predetermined number of vehicles may pass in one direction before the signal means is actuated 25 to signal approach of vehicles in an intersecting direction.

12. In a traffic signal, the combination with intersecting traffic lanes, of signal means for controlling traffic at the intersection, means for imparting signalling motion to said signal means including a pair of solenoids the cores of which are connected to said signal means, one of said solenoids operating to move the signal means in one 30 direction and the other solenoid operating to move the signal in the opposite direction, and means including a circuit establishing mechanism located in each traffic lane at each side of said intersection, means operable 35 by passage of a vehicle for actuating said circuit establishing mechanism to close a circuit through one of said solenoids to impart signalling motion to said signal means in one direction, and similarly located circuit 40 interrupting mechanism provided with vehicle operated actuating means for opening the circuit through the energized solenoid to thereby permit the previously closed circuit through the other of said solenoids to 45 impart signalling motion to said member in 50

the opposite direction, whereby not more than a predetermined number of vehicles may pass in one direction before the signal means is actuated to signal approach of vehicles in an intersecting direction. 55

13. In a traffic signal, a signal member, a solenoid for operating said member, means for establishing a circuit through said solenoid including a plurality of contact devices, means for operating said contact devices successively including a vehicle actuated member, and vehicle actuated means for interrupting the circuits so established including a plurality of electromagnets adapted to move said contact devices out of circuit establishing position and means for establishing a circuit through said electromagnets. 60

14. In a traffic signal, a signal member, means connecting said member with a pair of solenoids whereby said member is actuated to signal the approach of traffic travelling in one direction and the stoppage of traffic travelling in an intersecting direction and vice versa, means for establishing a circuit through one of said solenoids including 70 a plurality of contact devices capable of maintaining the circuit through one of said solenoids, vehicle actuated means for operating said contact devices successively during the passage of a number of vehicles whereby 75 one of said solenoids will hold said signal set during such passage of vehicles equal in number to the number of contact devices, a plurality of circuit interrupters, vehicle actuated means for operating said interrupters 80 successively to interrupt the circuits established by said contact devices, and a circuit breaker for breaking the circuit of all the aforesaid contact devices and permit actuation of the signal member due to the operation of a similar set of contact devices for establishing a circuit through the other of said solenoids to signal approach of traffic travelling in the intersecting direction. 85

In testimony whereof I have hereunto set 90 my hand this 28th day of June, A. D. 1921.

ALFRED W. RAM.
